UNITED STATES PATENT OFFICE.

ROBERT EZEKIEL WILSON AND ROBERT EUGENE WILSON, OF BELLEVILLE, NEW JERSEY, ASSIGNORS TO SEYMOUR R. GROSS, OF NEWARK, NEW JERSEY.

DROPPING MACHINE.

Application filed November 12, 1921. Serial No. 514,832.

To all whom it may concern:

Be it known that we, ROBERT EZEKIEL WILSON and ROBERT EUGENE WILSON, citizens of the United States, residing at Belleville, in the county of Essex and State of New Jersey, have invented certain new and useful Improvements in Dropping Machines; and we do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to an improved construction of dipping frame and loading mechanism therefor; and the invention has reference, more particularly, to a novel construction of frame for receiving and holding a plurality of wires, sticks or the like, together with a novel mechanism for automatically and simultaneously delivering the required number of said wires, sticks or the like, into operative assembled relation to the frame, and thereupon locking the same in such relation.

In the manufacture of pyrotechnical devices, such as sparklers, bengal lights and similar articles, a wire or stick is dipped into a proper pyrotechnical compound so that said compound is deposited upon a portion of the longitudinal extent of said wire or stick, and upon the proper drying and hardening of the compound the article is complete; the uncoated portion of the wire or stick serving as a handle for manipulating the article when used. The manufacturing process usually employed in the production of such articles consists in providing some form of frame or holder in which the wires or sticks are vertically disposed in symmetrical groups, each individual wire or stick being suitably spaced from the adjacent wires or sticks. The wires or sticks thus disposed are suitably secured to the frame or holder against accidental displacement, so that a considerable portion of their lengths depend from the frame or holder, and so that by a proper manipulation of the latter such depending portions of said wires or sticks may be thrust or dipped into a pyrotechnical compound to receive a coating thereof. Frames or holders of various kinds have heretofore been used, but have

been loaded or charged with the wires or sticks by hand; such method entailing a considerable consumption of both time and labor. It is the object of this invention to provide not only a novel construction of holder or frame for the wires or sticks, provided with a very simple and effective means for locking the latter therein against accidental displacement, but to also provide an automatic machine for delivering to and assembling in said novel holder or frame the required number of wires or sticks for fully loading the same, by a very simple and rapid method whereby the exact number of wires or sticks required to load the holder or frame are simultaneously dropped into the latter, thus saving a considerable amount of tedious and time consuming hand labor, while at the same time assuring the proper separately spaced disposition of each wire or stick relative to its fellows when locked in the said holder or frame.

Other objects of this invention, not at this time more particularly enumerated, will be clearly understood from the following detailed description of the same.

With the objects of this invention in view, the same consists, primarily, in the novel construction of dipping frame and loading mechanism therefor hereinafter set forth; and the invention consists, furthermore, in the novel arrangements and combinations of the various devices and parts, as well as in the details of the construction of the same, all of which will be hereinafter more fully described, and then finally embodied in the claims appended hereto.

The invention is clearly illustrated in the accompanying drawings, in which:—

Figure 1 is a front elevation of the novel loading mechanism with the novel dipping frame operatively associated therewith; Figure 2 is a vertical cross section through the same, taken on line 2—2 in said Figure 1; Figure 3 is a fragmentary rear side elevation of the loading mechanism, showing the cam for operating the wire tripping or releasing devices; Figure 4 is a detail horizontal section, taken on line 4—4 in said Figure 3; Figure 5 is a fragmentary vertical cross section of the wire feeding and releasing devices, drawn on an enlarged scale; Figure 6 is a detail fragmentary horizontal section, taken on line 6—6 in said

Figure 5, said view showing the wire releasing mechanism in initial wire retaining position; Figure 6^A shows the releasing mechanism operating to frictionally bind the wires against release; Figure 7 is a view similar to that shown in Figure 6, but showing the wire releasing mechanism as actuated to release the wires for delivery to the dipping frame; Figure 8 is a fragmentary 5 plan or top view of the novel dipping frame, with the top wall partially broken away to show the internal locking mechanism in elevation, said locking mechanism being also shown in initial released position; and Figure 9 is a view similar to that 10 shown in said Figure 8, but illustrating the locking mechanism in actuated operative relation to the wires assembled in said dipping frame.

15 Similar characters of reference are employed in all of the hereinabove described views, to indicate corresponding parts.

Referring now to said drawings, the reference character 10 indicates a pair of longitudinally spaced vertical standards, suitably supported upon foot-pieces 11, and joined together adjacent to their lower ends by a tie-rod 12. Secured to the upper extremity of each standard 10 is a forwardly projecting 20 bracket piece 13. Secured to and extending longitudinally between said bracket pieces 13 is a horizontal bridge plate 14. Supported upon said bridge plate 14 are a plurality of upwardly projecting tubular 25 containers 15. Said tubular containers are arranged in longitudinal rows, the corresponding members of the respective rows being transversely alined one with another. Said longitudinal rows of tubular containers 30 are also preferably arranged and disposed in two longitudinal equal groups, spaced apart laterally one from the other. The upper ends of said tubular containers 15 are suitably attached to a top plate 16, which 35 is supported by uprights 17 from said bridge plate 14, thus securely holding said containers against displacement from their vertically disposed relation to said bridge plate 14. Said bridge plate 14 is provided with 40 openings 18 axially alined respectively with the interiors of said tubular containers 15. Arranged in the bottoms of said tubular containers 15 are vertically movable agitator members 19 having depending shanks 20 45 projecting downwardly through said openings 18 of said bridge plate 14. The upper ends of said agitator members 19 are provided with concave seats 22. Said tubular containers 15 are each adapted to support in 50 upright position a plurality of sparkler wires 23. Said agitator members 19 and their shanks 20 are provided with axially or centrally disposed vertical discharge openings 24 of diameters substantially corresponding to the diameter of a single 55 sparkler wire 23, so that only one sparkler wire can pass endwise therethrough at a time. Disposed transversely beneath said bridge plate 14, and spaced downwardly therefrom, so as to be alined respectively 60 with the transverse rows of tubular containers 15, are transverse agitator bars 25 capable of a vertical or up and down vibratory movement. The opposite ends of said agitator bars 25 are supported upon guide 65 pieces 26 which are secured to the underside of said bridge plate 14 so as to depend therefrom, and which possess enlarged heads 26' which serve as stops for determining the downward limit of movement permitted to said agitator bars. Said agitator bars have their ends perforated or otherwise cutaway so as to operatively engage said guide pieces. The lower free ends of the shanks 20 of said 70 agitator members 19 engage and rest upon the upper surface of said agitator bars 25, and the latter are provided with openings 27 which are alined with the discharge openings 24 of said agitator members 19. Journaled in bearings 28 fixed to the underside 75 of said bridge plate 14, adjacent to the ends of the latter, is a longitudinal cam-shaft 29 provided with a cam portion 30 of polygonal cross sectional shape, as, for example, the hexagonal shape shown in the drawings 80. Said cam-shaft with its cam portion 30 extends longitudinally beneath the agitator bars 25 so as to operatively engage the central or intermediate portions 31 of the latter. As thus constructed and arranged 85 said cam-shaft and its cam portion is alined beneath the space intermediate the laterally spaced groups of tubular containers 15, thus permitting sparkler wire releasing means 90 to be mounted on either side of said cam-shaft in proper vertical alinement with the members of the respective laterally spaced groups of tubular containers. This arrangement permits the application of vertical 95 vibratory impulses to the central portions of said agitator bars 25, whereby the latter can best distribute said impulses equally to all the agitator members 19 engaged therewith. Secured on one end of said cam-shaft 29 100 is a driving pulley 32, by means of which 105 rotary motion may be transmitted to said cam shaft from any suitable source of power. The wire releasing means comprise longitudinally disposed supporting plates 33 which extend beneath said agitator bars 25, and which are secured by their respective ends to spacing blocks 34 fixed to the under side of said bridge plate 14, whereby the said supporting plates are 110 spaced downwardly from said bridge plate 120 a suitable distance providing clearance for the operative movement of said agitator bars 25. As thus disposed said supporting plates are 115 respectfully positioned beneath each group of tubular containers 15. Fixed to and sup- 120

125

130

ported by said supporting plates 33 are longitudinal rows of tubular guides 35 having axial or vertical passages 36 vertically aligned with the discharge openings 24 of said 5 agitator members 19 and with the openings 27 of said agitator bars 25 associated therewith. The transversely opposed members of each group of tubular guides 35 are provided on their inner or oppositely facing 10 sides with lateral openings or slots 37 intersecting said vertical passages 36 above the lower ends of the latter. Extending longitudinally between the rows of tubular guides 35 of each group of the latter is a 15 longitudinally movable releasing bar 38, slidably supported in connection with the under side of the supporting plate 33, by clip plate 39 secured to and spaced from the respective ends of the supporting plate 33 20 by spacing blocks 40 fixed upon the latter. The laterally opposed forward ends of the releasing bars 38 of the groups of tubular guides 35 are interconnected by a transverse tie-bar 41. Pivotedly mounted on a fulcrum 25 stud 42 depending from said bridge plate 14 is a lever 43, the inner end of which is pivotally connected to said tie-bar 41. The outer end 44 of said lever 43 projects outwardly from the rearward margin of said 30 bridge plate 14. It will be evident that the operation of said lever 43 will produce a simultaneous and equal longitudinal movement of said releasing bars 38, as will be clearly understood from an inspection of 35 Figure 4 of the drawings. Mounted upon the underside of said releasing bars 38 are a plurality of longitudinally spaced stop-spring devices, the transverse main bodies 45 of which are secured in place by screws 46, or by any other suitable means. Each stop device is provided, at the ends of the main body 45 thereof, with outwardly and forwardly inclined spring arms 47 terminating in longitudinal stop-projections 48. The 40 stop-projections 48 are normally disposed respectively in the lateral openings or slots 37 of said guides 35, and so as to offer either obstructions or frictional stops against the downward and outward passage of sparkler wires 23 through the vertical passages 36 of said guides 35 (see Figures 6 and 6^A). A forward movement imparted to said releasing bars 38 in the direction of the arrows α , shown in Figures 1, 4 and 6, will 45 carry said stop-projections 48 clear of the passages 36 of said guides 35, thereby removing obstruction to the downward and outward movement of sparkler wires 23 through the said guides (see Figure 7). 50 Mounted on said vertical standards 10, for vertical reciprocatory movement thereon, are slide pieces 49 which are connected together, at their upper ends, by a longitudinal carriage bar 50. Fixed in the angles formed at the 55 juncture of the lower ends of said standards 10 with the tie-rod 12 are socketed blocks 51 in which are inserted interchangeable vertical stop posts 52 which engage the lower ends of said slide-pieces 49 to determine the normal initial lowered position of the same and the carriage bar 50 supported thereby. 60 Connected with said foot-pieces 11, and forwardly spaced from said standards 10, are guide sockets 53. Mounted in said guide sockets 53, are vertical slide rods 54 having at their upper free ends enlarged heads 54'. Annular shoulders or collars 54'', which are fixed on said slide rods, engage the upper ends of said guide-sockets 53 to determine the normal initial lowered position of said 65 slide rods. Connected with said slide-pieces 49 are forwardly projected arms 55 which are perforated to engage over and slide upon said slide-arms. Said arms 55, when the slide-pieces 49 are actuated to move upwardly on the standards 10, slide upwardly upon the slide-rods 54 until they engage with the heads 54', whereupon an upward movement of proper stroke is imparted to said slide rods for purposes which will subsequently appear. Mounted on said slide-bars 54, so as to be vertically adjustable thereon, is a longitudinal support 56 upon which is fixed a horizontal stop-plate 57. The ends of said support 56 are provided with annular bosses 58, surrounding said slide-rods 54, which carry set-screws 59 for securing the support 56 and stop-plate 57 in desired vertically adjusted position on said slide rods 54. 70 75 80 85 90 95 100 105 110 115 120 125 130

Connected with said standards 10, so as to project rearwardly from the lower end portions thereof, are upwardly inclined bearing brackets 60 provided at their free ends with bearings 61 in which is journaled a rock-shaft 62. Suitably fixed on the right hand end of said rock-shaft 62 is an actuating lever 63. Fixed on said rock-shaft 62, in proper locations, are coupling sockets 64 which serve to secure to said rock-shaft forwardly projecting lever-arms 65. Projecting from the inward sides of said slide-pieces 49 are studs 66, and operatively interconnecting said studs 66 respectively with the forward free ends of said lever arms 65 are link-blocks 67. Also fixed on said rock-shaft 62, in desired locations, are other coupling sockets 68 which serve to secure to said rock-shaft rearwardly projecting lever-arms 69 upon the free ends of which are attached counter-balance weights 70. It will be understood that by imparting an upward swing to said actuating lever 63, the rock-shaft 62 will be turned rearwardly so as to throw upward the lever-arms 65. The upward swing of the lever-arms 65 is transmitted through said link-blocks 67 to said slide-pieces 49, thereby causing the same to slide upwardly on said standards 10 to thereby lift the carriage bar 50 to its upward limit.

Secured to said carriage bar 50 adjacent to its ends and so as to project forwardly therefrom, are carriage brackets 71, the upper faces of which are preferably provided with grooved seats 72. Said carriage brackets serve to support a novel detachable dipping frame in operative relation to the carriage device and to the loading mechanism for charging the same with the sparkler wires 23. 10 Pivottally connected with the ends of said carriage brackets 71 are latches or turn-buttons 73 for securing said dipping frame against accidental displacement from said carriage brackets. 15 The said novel dipping frame comprises a pair of horizontal plates 74, preferably made of sheet metal. Said plates 74 are secured together and vertically spaced apart by means of a central longitudinal intermediate spacing rib or block 75 to which they are attached by screws 76, or by other suitable fastening means. Said plates 74 are each provided with rows of longitudinally spaced openings 77, arranged so that the openings of one plate are vertically aligned with the openings of the opposite plate, and so that the grouping of the said openings 77 correspond to and respectively align themselves vertically with the discharge openings 36 of the guides 35 when the dipping frame is operatively attached to the carriage device of the loading mechanism. As thus arranged, the said openings 77 form two longitudinal groups, one on each side of said spacing rib or block 75. Slidably supported in the space intermediate the plates 74, so as to be respectively longitudinally movable between the longitudinal rows of each group of said openings 77, are slide-bolts 78. Guide posts 79 provided at each end of the dipping frame, and arranged in laterally opposed pairs, serve to retain the slide-bolts in position. Affixed to the sides of said slide bolts 78, are rearwardly and outwardly inclined lock springs 80, one for each set of vertically opposed openings 77. When said slide-bolts 78 are in normal rearwardly moved or released position, said lock-springs 80 are spaced rearwardly from the openings 77 with which they cooperate, and the rearward ends 81 of said slide-bolts 78 project outwardly from the end of the dipping frame (see Figure 8). Eccentrically pivoted between the outwardly projecting forward ends of said slide-bolts 78 is a rotary keeper-member 82, which may be turned to abut against the adjacent end of the frame, when said slide-bolts 78 are moved forward to operative position, thereby holding the latter against accidental displacement from such position. Fixed on the underside of the lower plate 74, adjacent to the ends of the frame, are transverse positioning ribs 83. When the dipping frame is deposited upon said carriage brackets 71, said ribs 83 seat themselves in the grooved seats 72 of said carriage brackets, thereby assuring a proper disposition of the dipping frame in required alinement with the loading mechanism. 70 The loading machine is provided with a means for locking the dipping frame after the same is charged with the sparkler wires 23, but before the frame is removed from the carriage brackets 72. This means comprises a transverse eccentric cam 84 rotatably mounted in connection with said carriage rod 50, so that when the same is turned to the left it will exert a forward push upon the ends 81 of the slide-bolts 78, thereby sliding the same to operative position. 75 Connected with the outer end of said eccentric cam 84 is a hand-lever 85 for actuating the same. 80 Fixed on one of said slide-pieces 49 is a vertical cam member 86 having a cam slot 87. This cam member 86 is so positioned that when the carriage device, (comprised of the slide-pieces 49 and carriage bar 50) rises, the cam slot will straddle or engage the free end 44 of the lever 43. The cam slot is so shaped that its cam-portion 88 will engage and impart to said lever 43 an operative movement as the carriage device approaches the upward limit of its movement, thereby assuring a timely operation of the wire releasing mechanism, as the dipping frame is carried to loading position beneath the ends of the guides 35. 85 In order to assure the complete retraction of the slide-bolts 78 to released position, before the dipping frame arrives at its loading position, a cam nose 89 is mounted to depend from said bridge-plate 14 in proper position to engage the forward ends of said slide-bolts 78 and to push the same back to 90 normal released position, as the dipping frame is carried to loading position. 95 Supported in upwardly spaced relation from said stop-plate 57, by uprights 90, is a longitudinal bar or supporting rod 91, to which are affixed a plurality of separator fingers 92, which project forwardly intermediate the stop-plate and the dipping frame. Said separator fingers 92, serve to guide the lower ends of the sparkler wires 100 23 as they pass downwardly through the dipping frame to stopped engagement with the stop-plate 57, and at the same time tend to maintain the wires upright in properly spaced longitudinal rows. 110 Having now described the detail construction of the dipping frame and loading mechanism therefor, it remains to briefly describe the operation of the same in use. 115 The tubular containers 15 are each filled with a plurality of sparkler wires 23, which stand endwise and upright therein, with their lower edges engaged or footing upon the concave seats 22 of the agitator members 19. Since said concave seats 22 slope at 120 125

all points toward the receiving end of the discharge openings 24, and since the agitator members are maintained in vertical vibration through the operation of the agitator bars 25 by the turning of the cam-shaft 29 which rotates its cam portion 30 operatively against said agitator bars, it follows that the tendency of the lower ends of the sparkler wires 23 is to move toward and into said discharge openings 24. Only one sparkler wire 23 can occupy each discharge opening 24 at a time, and the sparkler wires first gaining access to said discharge openings 24 drop downwardly therethrough so that their lower ends pass through the openings 27 of the agitator bars 25 and enter the passages 36 of the guides 35 until stopped by the normally positioned stop-projections 48 of the spring-stop devices associated with the releasing bars 38. The machine being supplied with sparkler wires 23, a dipping frame is placed upon the carriage brackets 71, and operatively secured to the carriage device. The operator now grasps the actuating lever 63 and by swinging the same upward operates the carriage device to raise the same (as above described) thereby moving the dipping frame upwardly to the guides 35, so that the openings 77 of the former register with the openings 36 of the latter. As the carriage device thus moves upward to wire receiving position, the cam member 86 engages and operates the lever 43 to thereby slide forward the releasing bars 38 so that the spring stop-devices with which the stop-projections 48 are connected are also moved forward to withdraw the latter from initial obstructing relation to the passages 36 of the guides 35. This operation releases the sparkler wires 23 entered in the guides, so that the same drop downward by gravity, their lower ends passing through the vertically aligned pairs of openings 77 of the dipping frame, and thence downwardly between the separator fingers 92 until stopped against the stop-plate 57. Before the carriage device reaches the upper limit of its movement and before the sparkler wires 23 are released from the guides 35, the arms 55 of the slide-pieces 49 approach and engage the heads 54' of the slide-rods 54, thereby exerting a lift upon the latter as the carriage device completes its upward movement, whereby there is imparted to the stop-plate 57 a limited upward movement which is timed to slightly raise the stop-plate simultaneously with the release of the sparkler wires. This raising of the stop-plate 57 limits the downward travel of the sparkler wires so that the upper ends of the latter do not quite clear or withdraw from the passages 36 of the guides 35, and consequently any following wires which drop down from the containers 15 cannot escape past the released wires while the wire releasing mechanism is in releasing position, since the lower ends of said following wires will be obstructed by the upper ends of said released wires which are still engaged in the lower ends of the passages 36 of the guides 35. The movement of the actuating lever 63 is now reversed, thereby lowering the carriage device to normal initial lowered position, which thus carries the dipping frame downwardly upon the upper ends of the sparkler wires 23, so as to leave the portions of the latter which are to serve as handles for the finished sparklers projecting above the dipping frame, while the portions thereof are to receive the coating of pyrotechnical compound project downwardly below the dipping frame. As the carriage device is thus returned to normal initial lowered position, the cam-member 86 reverses its operation upon the lever 43, thereupon moving the wire releasing mechanism back to holding relation to the following sparkler wires. Since, however, the following sparkler wires are most likely to be positioned so that their lower ends project beyond the slots 37, said stop-spring devices, when returned to holding position, will not necessarily move the stop-projections 48 into obstructing position, but rather said stop-projections 48 will engage the sides of the following wires under the tension of the spring arms 47 in the manner shown in Figure 6A of the drawings, thereby frictionally binding said following wires against the sides of the passages 36 of the guides 35, which relation, however, is equally effectual in holding the wires against dropping. By the time the following wires are thus engaged and held against dropping, the downward movement of the stop-plate 57 which accompanies the downward movement of the carriage device is completed, such downward movement of the stop-plate being sufficient to completely withdraw the upper ends of the released and dropped wires free from the guides 35. The dipping frame having been thus charged with the required number of sparkler wires, the same are ready to be locked securely thereto. The locking operation is accomplished by actuating the hand lever 85 to cause the eccentric cam 84 to push forward the slide-bolts 78 to locking position. In thus moving forward to locking position, said slide-bolts 78 carry the lock springs 80 against those portions of the sparkler wires disposed between the plates 74 and the vertically aligned openings 77 thereof, and cause the springs to exert a lateral pressure upon the wires which binds the wires against the margins of the openings 77 (as will be understood from an inspection of Figure 9 of the drawings). It is preferable to provide the outward margins of the openings 77 with notches 77' which approximate in 100 105 110 115 120 125 130

size the diameter of the wires, and into which the wires are forced by the pressure and tension of the lock-springs 80, when the latter operatively engage therewith. Such notches 77 provide a better grip upon the wires 23, and at the same time tend to firmly hold the same against displacement from the perpendicular when locked in the dipping frame. The wires 23 having thus 10 been locked to the frame in proper relation thereto, the eccentric rotary-keeper 82 is turned to obstruct accidental retraction of the slide-bolts, and consequently accidental release of the wires from the dipping frame.

15 Since the agitator members 19 continue in operation, it follows that as the first wires are displaced from the containers 15, second wires will gravitate to the discharge openings 24 to pass downwardly therethrough, 20 and thence to stopped position in the guides 35, consequently the first dipping frame is removed after being loaded, and a second dipping frame deposited upon the carriage device, whereupon the above described operations may be continued as often as desired.

25 In order to prevent accidental operation of the lever 43 (which controls the actuation of wire releasing mechanism) while the carriage device is in lowered position, a safety lock is provided, comprising a pivoted lock lever 93, having a lock-notch 94 in its side which normally straddles the end 44 of said lever 43, the free end of said lock-lever 93 carrying a weight 95 for holding the lock 30 lever in and returning the same to operative relation to the lever 43. Said lock-lever 93 is preferably pivotally secured to the rear end of the bracket arm 13 adjacent to said lever 43. When the cam member 86 rises 35 with the carriage device, it first contacts with and lifts said lock-lever 93 to free the lock-notch 94 from engagement with the lever end 44, so that the cam portion 88 is free to act on the latter. When the cam member 86 moves downward, the lock-lever 93 follows and operatively reengages said lever end 44 (all of which will be understood 40 from an inspection of Figure 3 of the drawings).

45 Since sparklers are made in various size lengths it follows, that vertical adjustment of the positions of the carriage device and the stop-plate 57 is desirable so that longer wires may be accommodated, and the locking position of the dipping frame relative to 50 said longer wires properly determined. To this end the stop posts 52 are made interchangeable, so that the carriage device may be raised or lowered to establish its normal initial position by using longer or shorter stop posts 52 as the circumstances require. Also the stop-plate 57 may be raised or lowered on the slide rods 54 according to need.

55 From the above description it will be apparent that we have provided a very ef-

ficient mechanism for the purposes in view, which automatically operates to assemble, at one stroke or simultaneously, a very large number of wires or sticks in proper spaced relation to a dipping frame or other holding device. The capacity of the machine is merely a matter of size. The length and number of the rows of containers 15 being variable according to the requirements of the case. In Figure 1 of the drawings we 70 have shown the ends of a machine with the central portion duplicating the container and associated structures broken away, since ordinarily the machine would possess the containers in longitudinal rows of considerable length, as, for example, four rows each possessing thirty-six containers 15, thus making provision for loading a dipping or other frame with one hundred and forty-four wires, adapting each frame to the process of manufacturing the articles in gross lots.

75 We are aware that some changes may be made in the arrangements and combinations of the various devices and parts, as well as 80 in the details of the construction of the same, without departing from the scope of our invention as set forth in the foregoing specification, and as defined in the appended 85 claims. Hence, we do not limit our invention to the exact arrangements and combinations of the various devices and parts as described in said specification, nor do we confine ourselves to the exact details of the 90 construction of said parts as illustrated in the 95 accompanying drawings.

100 We claim:—

1. In mechanism of the kind described, means for holding a supply of wires or the like, means for discharging wires from said holding means by gravity, wire releasing mechanism, a vertically movable carriage, a wire receiving means detachably mounted on said carriage, upward movement of said carriage device being adapted to carry said wire receiving means into operative relation to said wire releasing mechanism, means actuated by the upward movement of said carriage device for operating said wire releasing mechanism to drop wires into said wire receiving means, and a stop means for limiting the drop of released wires.

105 2. In a mechanism of the kind described, a plurality of containers for holding a supply of wires or the like, means for discharging wires one at a time by gravity from said containers, vertical guides below said discharging means to receive wires therefrom, releasable stop mechanism associated with 110 said guides to check the drop of said wires from said containers, a vertically movable carriage, a wire receiving means detachably mounted on said carriage, upward movement of said carriage being adapted to carry 115 said wire receiving means into operative 120 means.

- aligned relation to said guides, means actuated by the upward movement of said carriage for releasing said stop mechanism to drop wires into said wire receiving means, and means associated with said carriage for limiting the drop of said wires.
3. In mechanism of the kind described, a plurality of containers for holding a supply of wires or the like, means for discharging wires one at a time by gravity from said containers, vertical guides below said discharging means to receive wires therefrom, releasable stop mechanism associated with said guides to check the drop of said wires from said containers, a vertically movable carriage, a wire receiving means having wire locking devices detachably mounted on said carriage, upward movement of said carriage being adapted to carry said wire receiving means into operative aligned relation to said guides, means actuated by the upward movement of said carriage for releasing said stop mechanism to drop wires into said wire receiving means, means associated with said carriage for limiting the drop of said wires, and manipulatable means mounted on said carriage device for actuating said wire locking devices of said receiving means.
4. In mechanism of the kind described, a plurality of vertical containers for holding a supply of wires or the like, said containers being fixed in desired grouped and spaced relation one to the other, means for discharging wires one at a time by gravity from each container, vertical tubular guides aligned below said containers into which said wires pass, releasable stop mechanism for simultaneously releasing wires from said guides, a vertically reciprocable carriage device, means for reciprocating said carriage device, a holding frame detachably mounted on said carriage device, said holding frame having wire receiving means vertically aligned with said guides when said frame is attached to said carriage device, vertical slide rods, means mounting said slide rods, heads on said slide rods, perforated arms connected with said carriage device engaged over said slide rods beneath said heads, a stop-plate carried by said slide rods and disposed in downwardly spaced relation to said holding frame, an upward movement of said carriage device being adapted to move said holding frame into wire receiving relation to said guides, and means on said carriage device for tripping said releasable stop mechanism when said carriage is raised to drop wires into said holding frame, and means for limiting the drop of said wires through said holding frame.
5. In mechanism of the kind described, a plurality of vertical containers for holding a supply of wires or the like, said containers being fixed in desired grouped and spaced relation one to the other, means for discharging wires one at a time by gravity from each container, vertical tubular guides aligned below said containers into which said wires pass, releasable stop mechanism for simultaneously releasing wires from said guides, a vertically reciprocable carriage device, means for reciprocating said carriage device, a holding frame detachably mounted on said carriage device, said holding frame having wire receiving means vertically aligned with said guides when said frame is attached to said carriage device, an upward movement of said carriage device being adapted to move said holding frame into wire receiving relation to said guides, means on said carriage device for tripping said releasable stop mechanism when said carriage is raised to drop wires into said holding frame, and means for limiting the drop of said wires through said holding frame.
6. In a mechanism of the kind described, a plurality of vertical containers for holding a supply of wires or the like, said containers being fixed in desired grouped and spaced relation one to the other, means for discharging wires one at a time by gravity from each container, vertical tubular guides aligned below said containers into which said wires pass, releasable stop mechanism for simultaneously releasing wires from said guides, a vertically reciprocable carriage device, means for reciprocating said carriage device, a holding frame detachably mounted on said carriage device, said holding frame having wire receiving means vertically aligned with said guides when said frame is attached to said carriage device, vertical slide rods, means mounting said slide rods, heads on said slide rods, perforated arms connected with said carriage device engaged over said slide rods beneath said heads, a stop-plate carried by said slide rods and disposed in downwardly spaced relation to said holding frame, an upward movement of said carriage device being adapted to move said holding frame into wire receiving relation to said guides, and means on said carriage device for tripping said releasable stop mechanism when said carriage is raised to drop wires into said holding frame, said stop-plate being adapted for limited upward movement with said carriage device to stop the downward drop of said wires before they entirely clear said guides and while said releasable mechanism is tripped to thereby prevent outward drop of following wires from said guides until said releasable stop mechanism is returned to operative holding relation to said following wires.
7. In a mechanism of the kind described, a plurality of vertical containers for holding a supply of wires or the like, means for supporting said containers, an agitator member in the bottom of each container having a discharge opening permitting the passage of a single wire downwardly out of each container, the upper ends of said agitator members having concave seats surrounding said

discharge opening, and means for vertically vibrating said agitator members.

8. In a mechanism of the kind described, a plurality of vertical containers for holding a supply of wires or the like, means for supporting said containers, an agitator member in the bottom of each container having a discharge opening permitting the passage of a single wire downwardly out of each container, the upper ends of said agitator members having concave seats surrounding said discharge openings, means for vertically vibrating said agitator members, vertical tubular guides below and alined with the discharge openings of said agitator members, and releasable stop mechanism associated with said guides to check the drop of said wires from said containers.

9. In a mechanism of the kind described, a plurality of vertical containers for holding a supply of wires or the like, means for supporting said containers, an agitator member in the bottom of each container having a discharge opening permitting the passage of a single wire downwardly out of each container, the upper ends of said agitator members having concave seats surrounding said discharge openings, means for vertically vibrating said agitator members, vertical tubular guides below and alined with the discharge openings of said agitator members releasable stop mechanism associated with said guides to check the drop of said wires from said containers, a vertically movable carriage, a wire receiving means detachably mounted on said carriage, upward movement of said carriage being adapted to carry said wire receiving means into operative alined relation to said guides, means actuated by the upward movement of said carriage for releasing said stop mechanism to drop wires into said wire receiving means, and means associated with said carriage for limiting the drop of said wires.

10. In mechanism of the kind described, a plurality of vertical containers for holding a supply of wires or the like, means for supporting said containers, an agitator member in the bottom of each container having a discharge opening permitting the passage of a single wire downwardly out of each container, the upper ends of said agitator members having concave seats surrounding said discharge openings, agitator bars mounted for vertical vibratory movement beneath the supporting means of said containers, said agitator bars engaging said agitator members to vibrate the same vertically, said agitator bars having openings alined with the discharge openings of said agitator members, and a rotatable shaft having cam means for vibrating said agitator bars.

11. In a mechanism of the kind described, a plurality of vertical containers for hold-

ing a supply of wires or the like, means for supporting said containers, an agitator member in the bottom of each container having a discharge opening permitting the passage of a single wire downwardly out of each container, the upper ends of said agitator members having concave seats surrounding said discharge openings, agitator bars mounted for vertical vibratory movement beneath the supporting means of said containers, said agitator bars engaging said agitator members to vibrate the same vertically, said agitator bars having openings alined with the discharge openings of said agitator members, a rotatable shaft having 75 cam means for vibrating said agitator bars, vertical tubular guides below said agitator bars and vertically alined with the openings of said agitator bars and agitator members, and releasable stop mechanism associated 80 with said guides to check the drop of said wires from said containers.

12. In a mechanism of the kind described, a plurality of vertical containers for holding a supply of wires or the like, means for supporting said containers, an agitator member in the bottom of each container having a discharge opening permitting the passage of a single wire downwardly out of each container, the upper ends of said agitator members having concave seats surrounding said discharge openings, agitator bars mounted for vertical vibratory movement beneath the supporting means of said containers, said agitator bars engaging said 90 agitator bars having openings alined with the discharge openings of said agitator members, a rotatable shaft having cam means for vibrating said agitator bars, vertical tubular guides below said agitator bars and vertically alined with the openings of said agitator bars and agitator members, releasable stop mechanism associated with 95 said guides to check the drop of said wires from said containers, a vertically movable carriage, a wire receiving means detachably mounted on said carriage, upward movement of said carriage being adapted to carry said wire receiving means into operative alined relation to said guides, means actuated by the upward movement of said carriage for releasing said stop mechanism to drop wires into said wire receiving means, and means associated with said carriage for 100 limiting the drop of said wires.

13. In a mechanism of the kind described, a plurality of vertical containers for holding a supply of wires or the like, means for discharging wires one at a time by gravity from each container, vertical tubular guides 105 alined below said containers into which said wires pass, and releasable stop mechanism associated with said guides to check the drop of wires therefrom.

14. In a mechanism of the kind described,

a plurality of vertical containers for holding a supply of wires or the like, means for discharging wires one at a time by gravity from each container, guides having vertical 5 passages alined with said discharge means of said containers, said guides having lateral slots intersecting said vertical passage thereof, longitudinally slidable releasing bars adjacent to said guides, stop devices carried by said releasing bars, and said devices having outwardly inclined spring arms terminating in stop projections movable through said lateral slots of said guides to normally engage and check the drop of 10 wires from said containers through said guides.

15. In a mechanism of the kind described, a plurality of vertical containers for holding a supply of wires or the like, means for discharging wires one at a time by gravity from each container, guides having vertical 20 passages alined with said discharge means of said containers, said guides having lateral slots intersecting said vertical passage thereof, longitudinally slidable releasing bars adjacent to said guides, stop devices carried by said releasing bars, said devices having outwardly inclined spring arms terminating in stop projections movable 25 through said lateral slots of said guides to normally engage and check the drop of wires from said containers through said guides, a vertically reciprocable carriage, means for reciprocating said carriage, a holding frame detachably mounted on said carriage, said holding frame having wire receiving openings vertically alined with said guides when said frame is attached to said carriage, an upward movement of said 30 carriage being adapted to move said holding frame into wire receiving relation to said guides, a lever means for actuating said releasing bars, cam means on said carriage for operating said lever means and said releasing bars when said carriage is reciprocated, and means limiting the drop of wires through said holding frame.

35. In a mechanism of the kind described, a plurality of vertical containers for holding a supply of wires or the like, means for discharging wires one at a time by gravity from each container, guides having vertical 40 passages alined with said discharge means of said containers, said guides having lateral slots intersecting said vertical passage thereof, longitudinally slidable releasing bars adjacent to said guides, stop devices carried by said releasing bars, said devices having outwardly inclined spring arms terminating in stop projections movable 45 through said lateral slots of said guides to normally engage and check the drop of wires from said containers through said guides, a vertically reciprocable carriage, means for reciprocating said carriage, a holding frame detachably mounted on said carriage, said holding frame having wire receiving openings vertically alined with said guides when said frame is attached to said carriage, an upward movement of said 50 carriage being adapted to move said holding frame into wire receiving relation to said guides, a lever means for actuating said releasing bars, cam means on said carriage for operating said lever means and said releasing bars when said carriage is reciprocated, and means limiting the drop of wires through said holding frame.

55. In a mechanism of the kind described, a plurality of vertical containers for holding a supply of wires or the like, means for discharging wires one at a time by gravity from each container, guides having vertical 60 passages alined with said discharge means of said containers, said guides having lateral slots intersecting said vertical passage thereof, longitudinally slidable releasing bars adjacent to said guides, stop devices carried by said releasing bars, said devices having outwardly inclined spring arms terminating in stop projections movable 65 through said lateral slots of said guides to normally engage and check the drop of wires from said containers through said guides, a vertically reciprocable carriage, means for reciprocating said carriage, a

holding frame detachably mounted on said carriage, said holding frame having wire receiving openings vertically alined with said guides when said frame is attached to said carriage, an upward movement of said carriage being adapted to move said holding frame into wire receiving relation to said guides, a lever means for actuating said releasing bars, cam means on said carriage for operating said lever means and said releasing bars when said carriage is reciprocated, and means limiting the drop of wires through said holding frame, comprising vertical slide rods, heads on the upper ends of said slide rods, a stop-plate mounted between and carried by said slide rods to extend beneath said holding frame, and means connected with said carriage engageable with said slide rods to raise and lower the same and said stop-plate for the purposes described.

70. In a mechanism of the kind described, a plurality of vertical containers for holding a supply of wires or the like, means for supporting said containers, an agitator member in the bottom of each container having a discharge opening permitting the passage of a single wire downwardly out of each container, the upper ends of said agitator members having concave seats surrounding said discharge openings, agitator bars mounted for vertical vibratory movement beneath the supporting means of said containers, said agitator bars engaging said agitator members to vibrate the same vertically, said agitator bars having openings alined with the discharge openings of said agitator members, a rotatable shaft having cam means for vibrating said agitator bars, guides having vertical passages alined with the openings of said agitator bars and agitator members, said guides having lateral slots intersecting said vertical passages thereof, longitudinally slidable releasing bars adjacent to said guides, stop devices carried by said releasing bars, and said stop devices having outwardly inclined spring arms terminating in stop projections movable through said lateral slots of said guides to normally engage and check the drop of wires from said containers through said guides.

75. In a mechanism of the kind described, a plurality of vertical containers for holding a supply of wires or the like, means for supporting said containers, an agitator member in the bottom of each container having a discharge opening permitting the passage of a single wire downwardly out of each container, the upper ends of said agitator members having concave seats surrounding said discharge openings, agitator bars mounted for vertical vibratory movement beneath the supporting means of said containers, said agitator bars engaging said

agitator members to vibrate the same vertically, said agitator bars having openings alined with the discharge openings of said agitator members, a rotatable shaft having 5 cam means for vibrating said agitator bars, guides having vertical passages alined with the openings of said agitator bars and agitator members, said guides having lateral slots intersecting said vertical passages 10 thereof, longitudinally slidale releasing bars adjacent to said guides, stop devices carried by said releasing bars, said stop devices having outwardly inclined spring arms terminating in stop projections movable through said lateral slots of said guides to normally engage and check the drop of wires from said containers through said guides, a vertically reciprocable carriage, means for reciprocating said carriage, a holding frame 15 detachably mounted on said carriage, said holding frame having wire receiving openings vertically alined with said guides when said frame is attached to said carriage, an upward movement of said carriage being adapted to move said holding frame into 20 wire receiving relation to said guides, a lever means for actuating said releasing bars, cam means on said carriage for operating said lever means and said releasing bars 25 when said carriage is reciprocated, means limiting the drop of wires through said holding frame.

19. In a machine of the kind described, a plurality of vertical containers for holding a supply of wires or the like, means for supporting said containers, an agitator member in the bottom of each container having a discharge opening permitting the passage 30 of a single wire downwardly out of each container, the upper ends of said agitator members having concave seats surrounding said discharge openings, agitator bars mounted for vertical vibratory movement beneath the supporting means of said containers, said 35 agitator bars engaging said agitator members to vibrate the same vertically, said agi-

tator bars having openings alined with the discharge openings of said agitator members, a rotatable shaft having cam means for vibrating said agitator bars, guides having vertical passages alined with the openings of said agitator bars and agitator members, said guides having lateral slots intersecting said vertical passages thereof, longitudinally slidale releasing bars adjacent to 50 said guides, stop devices carried by said releasing bars, said stop devices having outwardly inclined spring arms terminating in stop projections movable through said lateral slots of said guides to normally engage and check the drop of wire from said containers through said guides, a vertically reciprocable carriage, means for reciprocating said carriage, a holding frame detachably mounted on said carriage, said holding frame having wire receiving openings vertically alined with said guides when said frame is attached to said carriage, an upward movement of said carriage being adapted to move said holding frame into 55 wire receiving relation to said guides, a lever means for actuating said releasing bars, cam means on said carriage for operating said lever means and said releasing bars when said carriage is reciprocated, means 60 limiting the drop of wires through said holding frame, comprising vertical slide rods, heads on the upper ends of said slide rods, a stop-plate mounted between and carried by said slide rods to extend beneath said holding frame, means connected with said carriage engageable with said slide rods to raise and lower the same and said stop-plate for the purposes described.

In testimony that we claim the invention 65 set forth above we have hereunto set our hand this 5th day of November, 1921.
